INVENTOR.

Israel Levin;

BY

G. S. Basy

ATTORNEY.

UNITED STATES PATENT OFFICE.

ISRAEL LEVIN, OF LOS ANGELES, CALIFORNIA.

SANITARY TOILET-SEAT PROTECTOR.

1,268,024.

Specification of Letters Patent. Patented May 28, 1918.

Application filed October 22, 1917. Serial No. 197,752.

To all whom it may concern:

Be it known that I, ISRAEL LEVIN, a citizen of the United States, residing at Los Angeles, in the county of Los Angeles and 5 State of California, have invented a new and useful Sanitary Toilet-Seat Protector, of which the following is a specification.

This invention relates to a protector for toilet seats and to a means for packaging 10 same.

Heretofore many attempts have been made to produce a satisfactory paper cover for toilet seats in public lavatories as the need of an article of this character has long 15 been recognized. The majority of these attempts have been commercial failures on account of the manner of packaging or dispensing the article, for example the bulk of packages or stacks of flat sheets renders 20 them inconvenient to handle and to dispose in small space, and the method of using rolls has not been generally adopted on account of waste and expense of maintaining a supply.

25 It is the object of this invention to provide a sheet paper toilet seat protector which is adapted to be folded into a compact space and to provide a container therefor by which the sheets may be arranged in 30 narrow stacks and dispensed from coin operated machines.

Another object is to provide a sheet so formed as to readily conform to the curvature of a toilet seat and to be retained there- 35 on against ready displacement.

Other objects will appear hereinafter.

The invention is illustrated in the accompanying drawings, in which:

Figure 1 is a view in perspective of the 40 paper sheet.

Fig. 2 is a perspective view showing the manner of folding the sheet.

Fig. 3 is a perspective view showing how the folded sheet is rolled to form a cone.

45 Fig. 4 is a perspective view illustrating the container with the folded and rolled sheet therein.

In carrying out the invention, I form an annulus 5 of paper of such size as to cover

the ordinary toilet seat and to project over 50 the outer and inner edges thereof. That the sheet may be conformed readily to the curvature of the seat surface, the paper employed is thin and craped being of the character commonly used in paper napkins and 55 tablecloths.

It is desirable to stiffen the edges of the sheet, particularly the outer edge, which is effected by coating the margin of the sheet with a border 6 of wax, such as paraffin or 60 the like. This also toughens and strengthens the sheet so as to prevent the edges from being readily torn.

As a means for facilitating bending the outer edge of the sheet down over the edge 65 of the seat, a series of small perforations 7 are formed around the sheet a short distance from its outer edge.

As a means for packaging the sheet and adapting it to be folded into a compact 70 space, it is provided with longitudinal fold lines 8, transverse fold lines 9, and diagonal fold lines 10, on which the sheet is folded into a segment of four double layers as shown in Fig. 2.

The sheet is then rolled into a cone as 75 shown in Fig. 3 and inserted in a cornucopia container 11, as shown in Fig. 4.

The containers and their contents may be pressed flat so that they will stack in narrow tiers, which permits their being handled by dispensing machines.

I claim:

1. A toilet seat protector comprising an annulus of craped paper having a waxed 85 margin and formed with perforations adjacent to its outer edge, said annulus having longitudinal, transverse and diagonal fold lines.

2. A toilet seat protector comprising an 90 annulus of craped paper having a waxed margin and formed with perforations adjacent to its outer edge, said annulus having longitudinal, transverse and diagonal fold lines, and a cornucopia container for 95 the reception of the annulus when folded and rolled.

ISRAEL LEVIN.
